UNITED STATES PATENT OFFICE.

JACOB HAEGE, OF GARFIELD, KANSAS.

FIRE-ESCAPE.

SPECIFICATION forming part of Letters Patent No. 299,132, dated May 27, 1884.

Application filed March 6, 1884. (No model.)

To all whom it may concern:

Be it known that I, JACOB HAEGE, a citizen of the United States, residing at Garfield, in the county of Pawnee and State of Kansas, 5 have invented certain new and useful Improvements in Fire-Escapes, of which the following is a specification, reference being had therein to the accompanying drawings.

This invention relates to improvements in fire-escapes; and it has for its object to provide means of escape from the upper stories of a burning building at any number of points which may be desired, and which, in the case of a hotel, may be put in operation from the 15 office or any other fixed locality. These objects are attained by the mechanism illustrated in the accompanying drawings, forming a part of this specification, in which—

Figure 1 is a front elevation. Fig. 2 is a plan. Fig. 3 is a detail view of bell-crank lever I, part of frame B, (in section,) cord K, and link S.

The letter A indicates a building provided with my fire-escape.

25 B is the frame of the machine.

C C' are rollers, upon which flexible ladders or ropes D, having knots at suitable intervals, are to be wound up. Each of these rollers has one or more notches in its periphery, which 30 are intended to receive the points of the pawls E, whereby the rollers are held in position when they have been wound up. Each pawl is connected to a T-shaped plate, M, by means of rods or links F. This plate is supported in 35 a horizontal position by a standard, G, and is pivoted thereto so that it may move freely in a horizontal plane, and at one end has a rod or link, S, by means of which it is connected

to a bell-crank lever, I, attached to one side of the frame B; from which is hung a cord, 40 K, which may be carried to the office (if the building is provided with one) or to any other place adapted to the purpose. The rollers C C' are each provided with a shaft, L, journaled to the frame B. The shafts L project outwardly from the frame, so as to receive a suitable handle, by means of which the rollers may be wound up. The frame may be attached to the outside of the building or to the roof in any convenient manner, and any number of rollers and plates M and chains, ladders, or knotted ropes may be employed—say one over each of the upper windows, whether there be two or more—and a pull upon the cord K will cause the whole number to descend and enable the 55 occupant of each room in the entire building to escape.

P are weights attached to the ends of the ropes or ladders, to cause them to descend more quickly.

Having thus described my invention, what I desire to secure by Letters Patent, and claim, is—

In a fire-escape, the frame B, and the rollers C C', having shafts L, provided with ropes or 65 flexible ladders D, in combination with pawls E, rods or links F, plate M, and bell-crank lever I, provided with cord K, substantially as described, and for the purposes set forth.

In testimony whereof I affix my signature in 70 presence of witnesses.

JACOB HAEGE.
